UNITED STATES PATENT OFFICE.

PEIRCE VAN VLECK AND HOWARD COOPER, OF BALTIMORE, MARYLAND, ASSIGNEES
TO WILLIAM H. PEIRCE, OF BALTIMORE, MARYLAND.

COMPRESSOR.

1,373,924.

Specification of Letters Patent.

Patented Apr. 5, 1921.

Application filed June 16, 1920. Serial No. 389,371.

To all whom it may concern:

Be it known that we, PEIRCE VAN VLECK and HOWARD COOPER, citizens of the United States, residing at Baltimore city, in the 5 State of Maryland, have invented certain new and useful Improvements in Compressors, of which the following is a specification.

This invention relates to compressors and 10 more especially of the class in which a liquid piston is employed and may be utilized to compress air, ammonia, or other gases.

The objects of the invention are,

First, to construct a compressor of the 15 liquid piston type to eliminate the usual stuffing boxes and at the same time provide a duplex pump having a single valve.

Second, to devise a compressor of the character referred to which is capable of rapid 20 and silent operation and at the same time avoid all dead centers, thereby insuring constant and uniform operation and long life.

Third, to construct and arrange the parts 25 in such a manner as to enable the compressor to be easily manufactured, assembled or taken apart for inspection or repairs in a minimum amount of time and cost.

Other objects and advantages of the invention will appear from the detailed description to be hereinafter given.

The invention consists of structural characteristics and relative arrangements of elements which will be hereinafter more fully disclosed and particularly pointed out in the 35 appended claims.

In the drawings in which similar reference characters indicate the same parts in the several figures of drawing—

Figure 1, is a longitudinal section taken 40 on line I—I of Fig. 2 with parts in elevation;

Fig. 2, is a section on line II—II of Fig. 1;

Fig. 3, is a section on line III—III of Fig. 1;

Fig. 4 is a section on line IV—IV;

Fig. 5 is a section on line V—V;

Fig. 6 is a section on line VI—VI;

Fig. 7 is a section on line VII—VII;

Fig. 8 is a section on line VIII—VIII; 50 and

Fig. 9 is a section on line IX—IX.

Referring to the drawings, 10 is a hollow base containing the reversing valve 11 whose specific construction and operation will be 55 presently described. Attached by any suit-

able means is a casting 12 provided with two compression chambers 13 and 14 having at their upper ends smaller float chambers 15 and 16 communicating therewith. 17, is a head closing the upper ends of the float 60 chambers 15 and 16 and is so cored, constructed and arranged to provide an inwardly opening intake-valve 18 and an outwardly opening discharge valve 19 for each of said float chambers 15 and 16 and coöperating compression chambers 13 and 14. Ports 20 and 21 lead respectively to the intake valves 18, and from the discharge valves 19, as shown and for the purpose to be later disclosed.

Within each of said float chambers 15 and 16 is arranged a hollow float-piston 22, adapted to receive, preferably a ball float 23 arranged to be seated in its upper position against an inner seat 24. Each of said float-pistons 22 has an upper opening 25 to permit the gas being pumped to pass through the float-piston 22 into and out of the chambers 13 and 14 by way of the openings 26 in the bottom section of said pistons 22, and said 80 openings 26 also allow high pressure liquid within the chambers 13 and 14 to actuate the ball floats 23 and pistons 22 for purposes to be later explained.

27 are knobs on the top of the float-pistons 85 22 which act as stops to arrest the upward movement of said pistons and insure a passageway being preserved between the upper ends of said pistons and intake valves 18 and discharge valves 19.

Formed in the hollow base is a fluid pressure chest 28 having a liner 29 in which the reversing valve 11 has a combined reciprocating and oscillating movement for purposes to be presently described. The ends of 95 the chest 28 are closed by the usual heads 30. Formed in the hollow base 10 is the high pressure liquid entrance passageway 31 which is in communication with the port 32 in the liner 29, and the lateral extensions 33, 100 33', of said passageway 31 communicate with ports 34, 34', in liner 29. 35 is the low pressure liquid discharge passageway having lateral extensions 36, 36', which open into and communicate with the low pressure 105 ports 37, 37', 38 and 38' in the liner 29, as shown. 39 and 40 are passageways connecting the interior of the compression chambers 13 and 14 with the interior of the center section of chest 28 on each side of 110

port 32. The reversing valve 11 within the chest 28 consists of three cylindrical sections 41, 42, and 43, said section 41 being provided with high pressure channels or 5 grooves 44, 44, and low pressure channels or grooves 45 and 45, which are adapted to register with the ports 34 and 38 respectively, while the high pressure channel or grooves 44', 44' and low pressure channels 10 or grooves 45', 45', in section 43 register respectively with the ports 34' and 38' during the operation of said valve 11 to be presently described, and it will be seen that 15 said high and low pressure grooves or channels 44, 44, 44', and 44' and 45, 45, 45' and 45' are arranged in pairs, equal and opposite to each other, to effect a circumferential balance of said valve to insure an easy, constant and uniform operation. The outer 20 ends of the valve sections 41 and 43 are provided with knobs or buttons 46, which act as stops and insure sufficient clearance between the ends of the valve 11 to provide an effective area for the end pressure to actuate 25 or reciprocate said reversing valve 11.

47, 47, are links, the upper ends of which are connected to the lower portion of the float-pistons 22, while their lower ends pass through the passageways 39 and 40 into the 30 chest 28 and slidably engage eccentric pins 48, 48 which pass through the cylindrical valve sections 41 and 43 and have their inner ends seated in depressions in valve section 42. These links 47, 47, are eccentrically arranged 35 or on each side of the longitudinal axis of the valve 11, so that reciprocation of said links 47, 47, oscillates the valve 10 through such an angle as to properly register the grooves or passageways in the valve 40 sections 41 and 43 with their coöperating parts in the liner 29.

The operation of the compressor is as follows:

Assuming that the ports 20, 20' are connected to a source of air or other gas supply which it is desired to compress, the port 21 is connected to a tank or chamber into which the compressed gas is to be supplied or stored, and the passageway 31 to a source 50 of liquid, preferably oil, under a hydrostatic head or pressure. The passageway 35 has communication with the suction side of a pump or other means for withdrawing the oil from the chest 28 and putting the same 55 under pressure for supply to the passageway 31, whereby the same oil can be employed over and over and insuring the constant lubrication of all the moving parts and avoiding the use of leaking glands or stuffing 60 boxes.

The valve 11 being in the position shown in Figs. 1 and 2, and so held in view of the high pressure channels 44', 44' of section 43 being in communication with the high pressure 65 ports 34', 34', and the low pressure

channels 45, 45, of section 41 being in communication with lower pressure discharge ports 38, 38, the oil under pressure passes through passageway 31, port 32 into chest 28 between valve sections 42 and 43, and 70 rises through passageway 40 into chamber 14 and displaces the gas in said chamber 14 and forces the same through openings 26, float piston 22, seat 24, opening 25 and discharge valve 19 into port 21 and in so doing 75 compresses said gas in the storage tank, not shown.

During the period in which the oil is being forced into and rising in said chamber 14, the oil in the chamber 13 is sinking and being withdrawn by the pump or other expedient through the passageway 39 into the chest 28 between the valve sections 41 and 42, and out by way of the port 37 and passageway 36, and the left end of the chest 85 28 is in communication with said passageway 36 through ports 45, 45, as will be readily understood.

As the rising oil in chamber 14 reaches the ball float 23, said float 23 is elevated in 90 the piston 22 and is forced against its seat 24, thereby shutting off any outlet of the oil through said piston 22, and the continuation of the rising of the oil level causes an unbalanced and excess of pressure to be exerted 95 on the inner surface of the upper end of piston 22, causing said piston with its connected link 47 to be elevated. This upward movement of the link 47 oscillates the valve 11 to such a position that the high pressure 100 channels 44, 44, in section 41 register with high pressure ports 34, 34, and the low pressure channels 45', 45', in section 43 register with ports 38', 38' and the valve 11, owing to differential pressures is made to move to the 105 right, and into such a position so that the valve section 43 uncovers the port 37', the valve section 41 passes over the port 37 and the section 42 is positioned to the right of port 32. It will also be readily understood 110 and seen that the float-pistons 22, 22, in the chambers 13 and 14 have reversed their positions, the piston in the chamber 13 being below that in chamber 14. In this new position of the valve 11 and when at the extreme 115 right in the chest 28, the oil under pressure passes from passageway 31 through port 32, passageway 39 into chamber 13, when the cycle of operations described with reference to chamber 14 is repeated and the oil within 120 chamber 14 is withdrawn through passageway 40, port 37', extension 36', passageway 35 to the pump not shown.

It will be seen that the passageways 39 and 40 have a double function of not only acting as ports for connecting the pressure chest 28 with the compression chambers 13 and 14, but at the same time act as gangways for links or other means to correctly 125 and directly convey the movement of the 130

float-pistons 22, 22, to properly and easily oscillate the reversing valve 11 without any use of stuffing boxes.

The length of the channels 45 and 45' is such that the ports 38 and 38' are cut off sufficiently early to effect a cushioning of the endwise travel or reciprocation of the valve 11, thereby assisting in making the compressor operate with the minimum of 10 noise.

From the foregoing disclosure of the construction, arrangement, assembling and mode of operation of the compressor, it will be seen that all of the objects and advantages 15 recited in the statement of invention are fully and efficiently carried out and while one embodiment of such an arrangement is herein illustrated and described, it will be readily seen that many changes will readily 20 suggest themselves to any one skilled in the art without departing from the structural characteristics and relative arrangement of elements covered by the claims.

What we claim is:

25 1. A fluid piston compressor comprising two compression chambers, each of which is provided with a cylinder communicating therewith, a gas inlet and a gas discharge for each cylinder, a float-piston within each cylinder having its interior in communication with a gas inlet and a gas discharge and a compression chamber, a float-valve 30 within each float-piston adapted to shut off communication between the gas discharge and interior of said hollow piston, a chest having an independent communication with each compression chamber at a point opposite to that of the cylinder, a combined oscillating and reciprocating valve having high and 35 low fluid pressure ports, and within said chest, means for connecting said float-piston with the combined oscillating and reciprocating valve for oscillating the valve by movement of the float piston, high and 40 low fluid pressure ports communicating with the interior of said chest and provided with passageways so constructed, arranged and disposed to coöperate with said valve within the chest and ports 45 in the valve to reciprocate said valve within the chest when oscillated by the float piston and alternately fill the compression chambers with the fluid under pressure and exhaust the same and permit the 50 fluid to enter and discharge from the chest.

2. A fluid piston compressor comprising two compression chambers, each of which is provided with a cylinder communicating therewith, a gas inlet and a gas discharge 55 for each cylinder, a hollow piston reciprocating in each cylinder having its interior in communicating with a gas inlet and a gas discharge and a compression chamber, means within each hollow piston adapted 60 to shut off communication between the gas

discharge and interior of said hollow piston, a chest having communication with each compression chamber at a point opposite to that of the cylinder, a combined oscillating and reciprocating valve having high and 65 low fluid pressure ports and within said chest, means connecting said hollow piston with the combined oscillating and reciprocating valve for oscillating the valve by movement of the hollow piston, high and 70 low fluid pressure ports communicating with the interior of said chest and provided with passageways so constructed, arranged and disposed to coöperate with said valve within the chest and ports in the valve 75 to reciprocate said valve within the chest when oscillated by the hollow piston and alternately fill the compression chambers with the fluid under pressure and exhaust the same and permit the fluid to enter and 80 discharge from the chest.

3. A fluid piston compressor comprising two compression chambers, each of which is provided with a cylinder communicating therewith, a gas inlet and a gas discharge 90 for each cylinder, a float-piston within each cylinder having its interior in communication with a gas inlet and a gas discharge and a compression chamber, a float-valve within each float-piston adapted to shut off 95 communication between the gas discharge and interior of said hollow piston, a valve chest, an independent passage connecting the valve chest with each compression chamber at a point opposite to that of the cylinder, a combined oscillating and reciprocating valve having high and low fluid pressure ports and within said chest, a link 100 passing through each compression chamber and independent passages and connecting said float-piston with the combined oscillating and reciprocating valve for oscillating the valve by movement of the float-piston, high and low fluid pressure ports communicating 105 with the interior of said chest and provided with passageways so constructed, arranged and disposed to coöperate with said valve within the chest and ports in the valve to reciprocate said valve within 110 the chest when oscillated by the float piston and alternately fill the compression chambers with the fluid under pressure and exhaust the same and permit the fluid to enter and 115 discharge from the chest.

4. A fluid piston compressor comprising 120 two compression chambers, each of which is provided with a cylinder communicating therewith, a gas inlet and a gas discharge for each cylinder, cut-off means within each cylinder adapted to shut off communication 125 between the gas discharge and interior of compression chamber, a chest having communication with each compression chamber at a point opposite to that of the cylinder, a combined oscillating and reciprocating 130

valve within said chest and having high and low fluid pressure ports, means connecting said cut-off means with the combined oscillating and reciprocating valve for oscillating the valve, high and low fluid pressure ports communicating with the interior of said chest and provided with passageways so constructed, arranged and disposed to coöperate with said valve within the chest and ports in the valve to reciprocate

said valve within the chest when oscillated and alternately fill the compression chambers with the fluid under pressure and exhaust the same and permit the fluid to enter and discharge from the chest.

In testimony whereof we affix our signatures.

PEIRCE VAN VLECK.
HOWARD COOPER.
